COVER REMOVER FOR SNAP-ON TYPE JAR COVERS

Melvin Lill, East Lansing, Mich.

Application October 28, 1953, Serial No. 27,367

Term of patent 7 years

(Cl. D44—29)

Fig. 2.

Fig. 1.

Fig. 3.

To all whom it may concern:

Be it known that I, Melvin Lill, a citizen of the United States, residing at East Lansing, in the county of Ingham and State of Michigan, have invented a new, original, and ornamental Design for a Cover Remover for Snap-On Type Jar Covers, of which the following is a specification, reference being had to the accompanying drawings, forming a part hereof.

In the drawings:

Figure 1 is a front elevational view of a cover remover for snap-on type jar covers showing my new design; Figure 2 is a top plan view of the same; and

Figure 3 is a side elevational view of the same.

I claim:

The ornamental design for a cover remover for snap-on type jar covers, substantially as shown.
